DESIGN FOR A VENDING MACHINE

Russel Wright, New York, N. Y.

Application February 5, 1940, Serial No. 90,025

Term of patent 3½ years

To all whom it may concern:

Be it known that I, Russel Wright, a citizen of the United States, residing at New York, in the County of Kings and State of New York, have invented a new, original, and ornamental Design for Vending Machines, of which the following is specification, reference being had to the accompanying drawing, forming a part thereof.

In the drawing:

The figure is a perspective view of a vending machine showing the front and one side thereof. The back of the machine is plain and the other side is similar to the side shown.

I claim:

The ornamental design for a vending machine, as shown and described.

RUSSEL WRIGHT.
